JOURNAL BOX LUBRICATOR PAD

William J. Sockell, Sr., Raleigh, N.C.

Application October 4, 1957, Serial No. 688,253

2 Claims. (Cl. 308—243)

This invention relates to a novel pad for lubricating journals of railway rolling stock and more specifically to an improved pad adapted to be mounted in the bottom of a journal box for more efficiently and uniformly supplying oil to a journal from the oil reservoir formed by the lower portion of the journal box in which the pad is contained.

Another object of the invention is to provide a pad of unique construction including spaced cores formed of a resilient cushioning material and which are disposed in circumferentially spaced relation to one another relative to a journal engaged by the pad and which resilient cores yieldably retain other wick-type portions of the pad in contact with the journal and with the oil of the oil reservoir for supplying oil through said wick-like pad portions by capillary action to the journal.

A further object of the invention is to provide a pad including a sack formed of a wick-like material in which the cores are contained in separate compartments of said sack and spaced apart from one another, and wherein passages are provided through the sack between the cushioning cores for the free passage of the lubricant from the reservoir to the portion of the pad in contact with the journal.

A further object of the invention is to provide a lubricator pad including a covering of a material possessing good absorbent characteristics and which covering substantially covers the side of the sack disposed adjacent the journal and is maintained in contact with the journal by the resilient core rolls to insure a constant, uniform and adequate supply of lubricant to the journal.

Still a further object of the invention is to provide a lubricating pad which can be quickly and easily applied to or removed from a journal box.

Other objects of the invention are to provide a pad which will withstand long and hard usage without deterioration and without a decrease in its efficiency, and which will not glaze and is lint free.

Various other objects and advantages of the invention will hereinafter become more fully apparent from the following description of the drawing, illustrating a presently preferred embodiment thereof, and wherein:

Figure 1 is a cross sectional view taken through the lower portion of a conventional journal box and showing the lubricator pad in an applied position and in transverse section along the line 1—1 of Figure 2;

Figure 2 is a fragmentary top plan view of the lubricator pad, on a somewhat reduced scale relative to Figure 1, and

Figure 3 is a longitudinal sectional view through the pad, taken substantially along a plane as indicated by the line 3—3 of Figure 2.

Referring more specifically to the drawing, the journal box lubricator pad in its entirety is designated generally 5 and comprises a sack, designated generally 6, formed of a lightweight duck fabric comprising an upper ply 7 and a lower ply 8, as best seen in Figures 1 and 3. Said plies 7 and 8 are secured together completely around

2

their marginal edges by stitching 9 to form the sack 6. The sack 6 is divided longitudinally by spaced substantially parallel rows of stitching 10 into spaced substantially parallel chambers or pockets 11. The spaced rows 5 of stitching 10 form a band portion 12 extending between the pockets 11 and which terminates in spaced relation to a front edge portion 13 and a rear edge portion 14 of the sack 6.

The pockets or chambers 11 each contains a resilient cushioning core 15 which maintains said pockets of the sack extended, as illustrated in Figures 1 and 3. The cushioning cores 15 may be formed of various materials suitable for the purpose but are each preferably composed of a plurality of strips 16 of a plastic material, each of which is relatively thick and similar in consistency and appearance to foam rubber. The strips 16 forming the cores 15 may be formed of polyester, which has proven very successful in tests made of the pad 5. This material is flexible and resilient, like other cushioning materials such as foam rubber or sponge rubber, and in addition possesses greater tensile strength and is much more stable when subjected to high temperatures than rubber or other cushioning materials, and is much less likely to assume a permanent set when subjected to pressures over prolonged periods of time, and in addition retains its flexibility and resiliency at very low temperatures. The material is also flame retardant and does not have the tendency to rebound or bounce back, as does foam rubber stock, so that it is more effective in maintaining the pad in contact with the journal at all times. While the cores 15 are not of circular cross section, the pockets 11, containing said cores and held distended thereby, possess a generally rounded shape.

The pad 5 also includes a fabric strip 17 which extends transversely across the outer side of the upper ply 7 of the sack 6 and which is secured by portions of the stitching 9 to the side edge portions of the sack 6, as seen in Figure 1, and which is also secured to the sack 6 by the spaced rows of stitching 10, so that an intermediate portion of the covering strip 17 constitutes an upper ply of the band 12. Said covering strip 17 is of a width substantially corresponding to the length of the cores 15 and is disposed substantially coextensive therewith, as seen in Figure 3. Said covering strip 17 is preferably formed of a knitted wool fabric which constitutes a good absorbing and conducting material for the lubricant 18 contained in the bottom reservoir portion 19 of the part of the journal box 20, as illustrated in Figure 1.

The lubricator pad 5 also includes several grommets 21 which extend through the plies of the front portion 13 of the sack 6, inwardly of and adjacent the stitching 9 of the front edge of the pad. The rear portion 14 is also provided with at least one grommet 21 and several grommets 22 are secured to the pad through the band portion 12 and are disposed between the rows of stitching 10. The grommets 21 assist in maintaining the sack closed and in relieving tension on the stitching 9. The grommets 22 assist in maintaining the band 12 between the pockets 11, relieve tension on the stitching 10, assist in retaining the strip 17 secured to the sack intermediate of its ends, and additionally provide lubricant passages 23 through the bores thereof, as will hereinafter be more fully described.

The pad 5 is adapted to be inserted in the lower reservoir portion 19 of the journal box 20 so that the lubricant conducting strip 17 will be disposed at the top of the pad 5 beneath and in contact with the underside of the journal 24 of said journal box. The pockets 11 and cores 15 form two spaced rolls of the pad 5 which are circumferentially spaced relative to one another with respect to the journal 24 and which are held in spaced apart relation by the band portion 12 of the pad which

is disposed therebetween. The pad 5 is flexible so that it can readily conform itself to the shape of the journal box bottom 19 and to the shape of the journal 24. The resiliency of the cores 15 will maintain portions of the strip 17, covering the upper parts of the two pockets or rolls 11, in yieldable contact with the journal 24. The duck material of which the sack plies are formed constitutes a good conductor for the lubricant 18 so that the lubricant will be conveyed by this duck material to the strip 17 and along the strip 17 by capillary action. In addition, the lubricant 18 will pass upwardly through the grommet passages 23 from the space between the rolls or pockets 11 and beneath the band 12 to the space thereabove. As this upper space or channel 25 is lined with a portion of the strip 17, additional lubricant will thus be supplied in this manner to said journal engaging strip 17 for maintaining a substantially uniform and adequate supply of the lubricant 18 at all times to the journal. Additionally, as the pad rolls 11, 15 expand and contract due to movement of the journal 24 toward and away from the reservoir bottom 19 the spaces 25 above the band 12 and 26 therebeneath will be enlarged and restricted for supplying additional lubricant through the passages 23 to the applicator strip 17.

The front portion 13 of the pad 5 is preferably located adjacent the open end, not shown, of the journal box 20, through which the pad is applied to and removed from the journal box, and one or more of the grommets 21 thereof may be utilized in effecting removal of the pad 5 from the journal box. The grommet 21 at the rear end 14 of the pad and one or more of the grommets 22 may be employed in connection with applying the pad 5.

Various modifications and changes are contemplated and may be resorted to, without departing from the function or scope of the invention as hereinafter defined by the appended claims.

I claim as my invention:

1. A journal box lubricator pad comprising a sack formed of a fabric material having an upper side and an underside, a forward end and a rear end, means dividing said sack longitudinally into transversely spaced pockets, a core disposed in each pocket, said cores being formed of resilient material for maintaining said pockets distended to form rolls, and an applicator strip secured to and overlying the upper side of said sack and con-

stituting an upper ply of each roll, said pad being adapted to be mounted in the bottom lubricant reservoir forming portion of a journal box and with the applicator strip at the upper side of the pad, the resilient cores of said rolls yieldably retaining circumferentially spaced portions of said applicator strip in contact with a journal of said journal box, said means dividing the sack into pockets comprising spaced substantially parallel rows of stitching connecting the upper and lower sides of the pad to one another and to an intermediate portion of said applicator strip to form a band portion of the pad between said pockets, said band portion spacing the pad rolls from one another and combining with portions of the pad rolls to provide channels above and beneath said band portion, and grommets mounted in and forming passages through said band portion near the ends and center thereof for the passage of the lubricant in the reservoir from the lower to the upper channel.

2. A journal box pad comprising an elongated fabric sack, means dividing said sack longitudinally into transversely spaced pockets, a core of a resilient cushioning material filling each of said pockets, said pockets and the cores contained therein combining to form pad rolls, said pad having an upper side and an underside, and a strip of fabric constituting a lubricant conveyor and applicator disposed over and secured to the upper side of the pad; said means dividing the sack into pockets comprising a band portion formed by abutting top and bottom portions of the sack, and grommets disposed in said band portion near the ends and center thereof and connecting said top and bottom sack portions, said band portion separating said pad rolls from one another and combining therewith to form upper and lower lubricant channels between said rolls and above and beneath said band portion, and said grommets forming lubricant passages between the channels.
